UNITED STATES PATENT OFFICE.

GOLDIE L. ANDERMAN, OF CHICAGO, ILLINOIS, ASSIGNOR TO KABO CORSET CO., OF CHICAGO, ILLINOIS, A CORPORATION OF WEST VIRGINIA.

BRASSIÈRE.

1,242,118.

Specification of Letters Patent.

Patented Oct. 9, 1917.

Application filed December 19, 1916. Serial No. 137,744.

To all whom it may concern:

Be it known that I, GOLDIE L. ANDERMAN, a citizen of the United States, residing at Chicago, in the county of Cook and State 5 of Illinois, have invented certain new and useful Improvements in Brassières, of which the following is a specification.

The present invention relates to an under garment commonly termed a brassière.

10 The principal objects of the invention are, to provide means located at the back of the brassière for permitting an adjustment of the body portion thereof, and to provide a back covering portion which will 15 overlie the eyelets and lacings that are provided to enable the adjustment feature to be carried out, so that said eyelets and lacings will not be visible through the outer garment of the wearer.

20 A further object of the invention is to arrange this back covering portion in a manner whereby it can be drawn taut, thus smoothing out any bulging of the flesh that may be present on the back of the wearer 25 through the use of a corset.

A further object of the invention is to attach this back covering portion to the shoulder straps of the brassière, whereby when said covering portion is drawn into 30 position it will exert a pressure upon the shoulder straps, tending to prevent their slipping off from the shoulders of the wearer.

The invention further consists in the features of construction and combination of parts hereinafter described and claimed.

In the drawings:

Figure 1 is a perspective of the brassière of the present invention, with the ends of 40 the covering portion unsecured;

Fig. 2, a perspective of said brassière, with the ends of the back covering portion secured, and said portion drawn taut; and

Fig. 3, a sectional detail, showing the connection between the back covering portion and one of the shoulder straps.

In the art to which the present invention relates, so far as I am aware, a brassière has never been constructed capable of adjustment in the manner of a corset, and furthermore, the brassières of which I am aware are made to smooth out the bulging flesh at the front of the wearer, but make no provision for smoothing out such bulging at the back of the wearer. A further

difficulty has existed in the brassière garments of which I am aware by reason of the shoulder straps slipping off from the shoulders of the wearer.

Referring now to the drawings, the garment as therein shown comprises a section 4 and a section 5. The section 4 is formed along one edge with a series of eyes 6, and the section 5 is formed along an adjoining edge with a series of hooks 7 adapted to engage with the eyes 6. This makes a detachable connection between the sections of the front of the garment, although the means employed for such detachable connection may be varied from the hook and eye construction.

The opposite edge of the section 4 is formed with a series of eyelets 8, and the edge of the section 5 adjoining thereto is formed with a series of corresponding eyelets, not shown. Both sets of eyelets are positioned at the rear of the garment, as will be clearly understood from the drawing, and these eyelets receive a lacing cord 10. This enables the edges of the sections 4 and 5 at the rear of the garment to be adjusted with respect to one another to vary the space therebetween, thus permitting of an adjustment of the entire garment after the manner in which corsets are adjusted.

A brassière is worn directly beneath the outer clothing. It would be unsightly and impractical to employ the eyelets and lacings at the back of the brassière without a covering member, since if there were no covering member provided, the eyelets and lacings would show through the outer waist of the wearer, making the garment unsightly and rendering it commercially impractical. I therefore provide a fabric back covering 90 portion 11, consisting of a part 12 extending across the back of the brassière. This covering portion may, if desired, be provided with an embroidered surface, so as to obtain an artistic appearance when viewed through the outer garment of the wearer.

Oppositely tapered tab-like parts 13 are provided, which extend from the lower edges of the part 12 to the front of the brassière; and the tabs 13 are in fact a part of the back covering portion 12. Connected to the ends of these tabs are strings or tape members 14, which can be tied together at the front as illustrated in Fig. 2. The covering portion is further provided with tabs 15 (two in 110

number), each of which is attached to a shoulder strap 16 of the brassière.

It is obvious that when the tapes 14 are tied, the back part 12 of the covering portion will overlie the eyelets and lacings at the back of the brassière, so as to conceal them from view. Also, when the covering portion is stretched and tied as in Fig. 2, it will exert a pressure upon the back of the wearer, tending to smooth out any bulging of the flesh that may be present at this point. Furthermore, the tension of the covering portion will be exerted through the tabs 15 onto the shoulder strap 16, and will thus prevent said straps from slipping from the shoulders of the wearer.

To summarize, by the use of this back covering portion, I accomplish three functions: First, I effect the concealment of the lacings and eyelets at the back of the brassière, thus producing a practical adjustable brassière; second, I provide a portion at the back of the brassière which can be stretched and placed under pressure to smooth out any bulging flesh at this point; and, third, I place a tension or pressure on the shoulder straps, tending to prevent them from slipping from the shoulders of the wearer.

I claim:

30 1. A brassière comprising two sections, means arranged along adjoining edges of said sections at the front of the garment for detachably connecting the sections together, means at the back of the garment for permitting an adjustment between the sections to vary the size of the garment, a covering

portion arranged to overlie and conceal said adjusting means, said covering portion extending across the back of the garment and secured to said garment at points adjacent the upper edges of the back of the garment and disconnected at all times at all other places from said garment, and fastening members secured to the lower ends of the covering portion, said fastening members 45 being adapted to extend to the front of the wearer and be secured at that point, and when so secured placing a strain downwardly and forwardly on the covering member whereby said member will tend to 50 smooth out bulging flesh at the back of the wearer, substantially as described.

2. A brassière comprising two sections, each formed with a shoulder strap, means arranged along adjoining edges of said sections at the front of the garment for detachably connecting them together, means at the back of the garment for permitting an adjustment between the sections to vary the size of the garment, a covering portion arranged 55 to extend across the back of the garment and to overlie and conceal said adjusting means, said covering portion being attached to the shoulder straps of said garment, means for securing said covering portion in place, and said portion when secured acting to smooth out bulging flesh at the back of the wearer and acting to place a strain upon the shoulder straps to prevent slippage thereof, substantially as described.

GOLDIE L. ANDERMAN.
